[57] CLAIM

The ornamental design for terminal connector cover, as
shown and described.

DESCRIPTION

FIG. 1 is a plan view of the terminal connector cover.
FIG. 2 is an inverted plan view of terminal connector
cover.

FIG. 3 is a front view of the terminal connector cover.
FIG. 4 is a rear view of the terminal connector cover.
FIG. 5 is a view of one side of the terminal connector
cover.

FIG. 6 is a cross-sectional view on the line 6—6 in FIG.
4 of the terminal connector cover.

FIG. 7 is a view of the other side of the terminal con-
nector cover.

FIG. 8 is an enlarged cross-sectional view on the line
8—8 in FIG. 4 of the terminal connector cover.
